UNITED STATES PATENT OFFICE.

FRIEDRICH BALASSA, OF BUDAPEST, AUSTRIA-HUNGARY, ASSIGNOR TO MAGYAR KIR. ALLAMI VASGYÁRAK KÖZPONTI IGAZGATOSÁGA, OF BUDAPEST, AUSTRIA-HUNGARY.

CARBURETER.

1,151,989.

Specification of Letters Patent. Patented Aug. 31, 1915.

Application filed February 21, 1914. Serial No. 820,233.

To all whom it may concern:

Be it known that I, FRIEDRICH BALASSA, of Budapest, Austria-Hungary, a subject of the King of Hungary, and whose post-office address is Rezsö tér No. 1, Budapest, X, Kingdom of Hungary, Austria-Hungary, have invented new and useful Improvements in Carbureters for Internal-Combustion Engines, of which the following is a specification.

This invention relates to spray carbureters for internal combustion engines and has for its object to construct an improved carbureter of this type in which the nozzle consists of a pipe with a row of fine jets or perforations lying close together, arranged at an angle in the direction of the throttle valve which is located in a correspondingly broad horizontal air suction channel attached to the valve box at the valve height. By this construction the drawn-in fuel is sprayed and dispersed in the direction of the throttle valve in a row of fine jets close together and is also drawn in a straight direction in the valve chamber.

An important advantage of the improved carbureter is that in spite of its great simplicity, inasmuch as every air nozzle is omitted as well as the complicated concentric arrangement of air nozzles and fuel nozzles with the accompanying difficulty of adjustment and necessity of renewal for the different cylinders, an exceedingly advantageous capacity for operation is the result.

A special feature is that in the improved device the finely divided fuel is directly drawn along a straight passage in the valve chamber, which is of special importance for starting and speeding up the engine.

Up to the present time with the types of spray carbureter held to be most reliable an aspirator is regularly necessary for the fuel with a twisted outward passage, and this makes the quick speeding up of the engine, especially in cold weather, very difficult so that with each spray carbureter a special starting atomizer is provided or where this is not the case, still a special benzine starting switch is needed close to the carbureter on a benzine motor. This drawback does not exist with the carbureter of the present invention because the turning of the motor is sufficient, on account of the horizontal direction of the straight passage and in con-

junction with the special formation of the broad nozzle, in order to bring the necessary mixture into the fuel chamber for speeding up without further difficulty. In operation also, in spite of the omission of a special air nozzle which must be changed for engines with a different normal number of revolutions, the present invention proves exceedingly economical and suitable, and in particular renders unnecessary the troublesome work of changing and mutually adjusting the fuel nozzle and air inlet.

The accompanying drawing shows, by way of example, one method of carrying out the invention.

Figure 1 is a section on the broken lines A—B—C—D of Fig. 2; Fig. 2 shows an end view of the carbureter, and Fig. 3 shows the air inlet valve.

The fuel container *a* with float *b* may be of any suitable construction. The fuel which is kept in the container at a constant level, indicated at *c*, is admitted into a lateral branch-pipe *d* with the usual needle valve *e*. According to the invention the casing *f* is secured to a branch pipe *d* and as shown, has a rectangular cross section. In said casing, a throttle valve *g* is journaled by means of a shaft which carries a lever *h* connected to the governor rod.

Under the throttle valve and raised a little the nozzle pipe *i* is fixed and secured by a nut *j*. The nozzle pipe has a number of fine nozzles or perforations *k* arranged side by side and as shown in Fig. 2 in a direction inclined to the throttle valve. Said throttle valve is movable from its inclined position in which it closes the channel through casing *f* to a position in which it fully opens said channel. The axes of the inlets *k* are substantially perpendicular to said valve when the latter is in a position midway between its open and closed positions. The casing *f* has a connection flange *l* by which it is directly connected to the valve chamber of the engine and is provided with a cover *m* at its opposite end with an adjustable air inlet port of any suitable description. The casing *o* of a secondary air valve *p* which can be of any suitable construction leads into the suction passage. It is, however, essential that this secondary air valve is located behind the throttle valve, that is to say nearer to the engine inlet valve

as shown in Fig. 2, so that even when the throttle valve is quite closed a constant supply of fresh spare air can be admitted through the secondary air valve into the cylinder. During the suction stroke the fuel in a row of fine jets is caused to impinge more or less directly against the throttle valve in accordance with the inclination of said valve and is finely dispersed or atomized in an exceedingly effective way. Owing to the slope of the throttle valve toward the horizontal floor of the suction passage a nozzle-like operation results so that the sprayed mixture is drawn directly into the valve chamber by a short straight passage. When the throttle valve is closed, as already stated, fresh air is drawn through the secondary valve for the scavenging the residual gas in order to prevent undesired repeated explosions in the cylinder.

What I claim is:

1. In a carbureter, the combination of a casing provided with an air suction channel which is relatively broad in comparison to its depth, fuel inlets arranged in a series transversely of said channel, and a butterfly valve arranged in said channel on an axis extending transverse thereto, said valve being arranged to intercept the fuel from said inlets and constituting a wall movable toward and away from said inlets.

2. In a carbureter, the combination of a casing provided with an air suction channel fuel inlets arranged in a series transversely of said channel, and a butterfly valve movable on an axis extending transverse to said channel into full open and closed positions and constituting a wall movable toward and away from said inlets, said inlets being arranged in a position perpendicular to the plane of said valve when the latter is in its middle position.

3. In a carbureter, the combination of a casing provided with an air suction channel which is relatively broad in comparison to its depth, fuel inlets arranged in a series transversely of said channel, and a butterfly valve arranged in said channel on an axis extending transverse thereto, said valve being arranged to intercept the fuel from said inlets and constituting a wall movable toward and away from said inlets, said inlets

being inclined inwardly toward said butterfly valve.

4. In a carbureter, the combination of a casing provided with an air suction channel which is relatively broad in comparison to its depth, fuel inlets arranged in a series transversely of said channel, and a butterfly valve arranged in said channel on an axis extending transverse thereto, said valve being arranged to intercept the fuel from said inlets and constituting a wall movable toward and away from said inlets, said inlets being arranged in a position perpendicular to the plane of said valve when the latter is in its middle position.

5. In a carbureter for internal combustion engines, the combination with a valve casing having a horizontal passage therein, a tubular passage extending transversely of said passage and therebelow, said tubular passage being provided with inlet openings presented upwardly into the first said passage, a butterfly valve journaled on an axis parallel to said tubular passage, an air inlet valve at one end of the first mentioned passage and on the same side of the butterfly valve as said inlet openings thereinto.

6. In a carbureter for internal combustion engines, the combination with a valve casing having a horizontal passage therein, a tubular passage extending transversely of said passage and therebelow, said tubular passage being provided with inlet openings presented upwardly into the first said passage, a butterfly valve journaled on an axis parallel to said tubular passage, an air inlet valve at one end of the first mentioned passage and on the same side of the butterfly valve as said inlet openings thereinto, said valve casing being provided with a secondary air inlet valve communicating with the first mentioned passage on the opposite side of said butterfly valve from said inlet openings.

In testimony whereof I have hereunto set my hand in presence of two subscribing witnesses.

FRIEDRICH BALASSA.
